CLAIM

The ornamental design for a non-slip hosiery, as shown and described.

DESCRIPTION

FIG. 1 is a perspective view of a non-slip hosiery showing the upper portion of the hosiery in a worn position;
FIG. 2 is a top plan view of a non-slip hosiery shown separately from the upper portion of the hosiery for ease of illustration;

FIG. 3 is a bottom plan view thereof.

FIG. 4 is a front elevational view thereof.

FIG. 5 is a rear elevational view thereof.

FIG. 6 is a right side elevational view thereof; and,

FIG. 7 is a left side elevational view thereof.

The broken lines shown in FIG. 1 represent the upper portion of the non-slip hosiery as environment and form no part of the claimed design.

The double line around the outer edges in FIG. 2 represent the thickness of material. The interior contours shown in FIG. 2 follow the exterior contours shown throughout the views.

1 Claim, 4 Drawing Sheets
